United States Patent Office.

AMOS WESTCOTT, OF SYRACUSE, NEW YORK.

Letters Patent No. 77,144, dated April 21, 1868.

IMPROVEMENT IN CHURNS.

The Schedule referred to in these Letters Patent and making part of the same.

TO ALL WHOM IT MAY CONCERN:

Be it known that I, AMOS WESTCOTT, of the city of Syracuse, in the county of Onondaga, and State of New York, have invented a new and useful Improvement in Churns; and I do hereby declare that the following is a full and exact description thereof, reference being had to the accompanying drawings, and to the letters of reference marked thereon.

To enable others skilled in the art to make and use my invention, I will proceed to describe its construction and operation.

A, Figure 1, in the accompanying drawings, represents the box or body of the churn. B and B represent a portion of the dasher, seen by breaking away a portion of said box; C, the front view of a fan-wheel blower, for the purpose of forcing a current of air through the churn; D, an enlarged rim of the pinion-wheel E, which acts against a friction-roller, r, to drive the fan-wheel; F is a driving-wheel, geared into the pinion E, and revolved by the crank H.

In constructing my churn, I make the box conical or pyramidal, or a combination of the two forms, as in the drawing, in which the lower half of the body is a section of a hollow cone, and the upper portion a section of a hollow pyramid, the sides of both making the same angles with the base or large end of the churn. This box is placed upon legs, so as to stand, when in use, with its ends perpendicular, and its axis horizontal, or approximating this position.

Figure 2 represents the dasher, which, in its general figure, is also conical. A representing the main shaft, B a metallic ferrule, with bifurcated projections f and f, to couple it with the shaft of the pinion-wheel. The paddles a a a a, b b b b, c c c c, d d d d, are set upon the shaft diagonally, and are so cut that their faces will tend to throw the fluid, which they strike in their revolutions, towards the apex of the box, or up the incline made by the bottom of the box. These are represented in the drawings as bevelled at an angle of forty-five degrees, but I do not confine myself to this angle; the amount which they should be bevelled depending upon the angle made by the bottom of the box with the base or large end of the churn.

These paddles are set about the shaft in a spiral form, and are upon four sides of it only. These dasher-paddles are made of any convenient size, and form rectangular pieces, with their opposite corners cut away till the paddles are left of a proper thickness, and when attached to the shaft, the face of each is at the same angle with the line of the shaft. Their length in any given row constantly varies, growing shorter from the large or gear end of the churn to the opposite end, and are of such length at any given point as to correspond with the inside diameter of the cone constituting the box at that point; the end of each working close to the periphery of the circle of the churn-box, wherever it may be located.

In Figure 3, A represents the pinion-wheel; B, its shaft, which passes through the end of the churn, and terminates in the conical point b, which enters into the hole e, fig. 2, in the end of the main shaft, and serves to guide and support the latter in position.

Near the end b, fig. 3, this pinion-shaft has a cross-bar, a a, which fits into the bifurcations on ferrule B, fig. 2, and by which the main shaft is driven.

Figures 4 and 5 represent an adjustable leg, which is attached to the small end of the churn. In fig. 4, A represents a plate, which is screwed fast to the said end of the churn, having a projecting plate, B, made at right angles with the plate A, to which is attached the leg C*. The projecting plate B stands vertically, and is firmly attached to the plate A, or is cast as a part of the same piece, and is provided with a centre spur or pivot, g, which passes through a slot, c, fig. 5, to guide the leg, and to hold it to the plate B. This plate is also provided with smaller pivots or pins, a, b, c, d, e, f, for purposes hereafter to be described. The portion of the leg C* is made flat, so as firmly to lie against the plate B, and has a bifurcation at the upper extremity h, made to embrace the pins a, b, c, d, e, f.

The leg is held against the plate B by the washer k and cross-pin m, and is moved up and down on the centre-pin g. If the leg is in the position represented in the drawing, fig. 4, it is held from moving backward

or forward by the bifurcation *h*, embracing the pin *c* and the slot *e*, fig. 5, embracing the centre-pin *g*. The lower part *D** of the metallic portion of the leg is a socket, to receive the upper end of the main or wooden portion of the leg *E**.

When the different parts are in their respective positions as above described, if the end of the churn be raised by lifting upon the handle *n*, fig. 4, the weight of the leg withdraws the bifurcation *h* from the pin *c*, and the leg is free to move backward and forward about the centre-pin *g*, and may be carried to any desirable angle with the end of the churn.

In fig. 1, *C* represents a fan-wheel blower, which has orifices *fff* near its centre for the ingress of air. From the box enclosing the fan-wheel there are projections *b* and *d* coming off at right angles with the sides, and set opposite each other. The projection *d* is held by the head of the screw *c* firmly against the end of the churn, while the projection *b* is bifurcated, and passes astride and under the shoulder of the thumb-screw *e*. This thumb-screw is used to secure the box or case firmly in place, and also to regulate the friction of the roller *z* against the rim *D*. Projecting from the back or under side of the box, and represented by the dotted lines *ff*, fig. 1, is a metallic tube, which terminates on the inner surface of the bottom of the box, and opens into it. This tube serves the purpose of steadyng the box, and for conducting the air from the box into the churn. It also serves as a centre, around which the box is moved to attach it to or disengage it from the end of the churn.

Figure 6 represents the fans, and the direction they are inclined to gather and direct the air towards the orifice *b*, and thence through the tube represented by the dotted lines *cc*.

Figure 7 represents another view of these fans, by the dotted lines *aaa*, the orifice or open end of the tube *b*, the direction of the air by the arrow *e*, and its exit through the cover of the churn through the tube *d*.

When the churn is worked, the operator is supposed to stand on the side of the churn, bringing the gear-end at his right hand, and the dasher moves towards him, or in the direction of the arrows *x* and *y*, fig. 2. It is evident that the fluid will be thrown diagonally by its operation towards the operator, and equally towards the small end of the churn, or up the inclined plane made by the bottom of the churn. The fluid will not, of course, remain here, but will, by its own gravity, return to the lowest part of the churn. The operation will resemble the stirring or whipping of cream with a spoon or ladle in an inclined bowl. In this way a constant interchange among the particles of fluid is effected. When the process of churning is completed, the butter may be withdrawn from every other part of the churn to the gear-end by reversing the motion of the dasher-paddles. These being bevelled on their opposite sides, and set in a spiral form, and aided by gravity, the butter may be easily gathered at this part of the churn. When this process is completed, by the use of the adjustable leg on the small end of the churn, this end may be lowered to any desirable inclination to draw off the butter-milk, while the butter is retained in place by the dasher-paddles.

If water is employed in washing the butter, this may be treated in the same manner, and separated from the butter in the manner above indicated. Another marked advantage is gained by this form of box and dasher—that of enabling us to churn the smallest possible amount of milk or cream. A single pint of fluid will settle so as to be in reach of the longest paddles, whose action upon it will bring it in contact with all of the other paddles.

What I claim as my invention, and desire to secure by Letters Patent, is—

The combination of the conical body, adjustable leg, horizontal dasher-shaft, and alternately oblique dashers, and fan-wheel, substantially as described, for the purposes set forth.

AMOS WESTCOTT.
